US0D1097918S

(12) **United States Design Patent** (10) **Patent No.:** **US D1,097,918 S**
(45) **Date of Patent:** **** Oct. 14, 2025**

(54) **REAR BUMPER**

(71) Applicant: **VOLVO CAR CORPORATION**,
Gothenburg (SE)

(72) Inventor: **Honghao Chen**, Gothenburg (SE)

(73) Assignee: **Volvo Car Corporation**, Gothenburg
(SE)

(**) Term: **15 Years**

(21) Appl. No.: **29/933,193**

(22) Filed: **Mar. 18, 2024**

(30) **Foreign Application Priority Data**

Sep. 28, 2023 (EM) 015035562-0003

(51) **LOC (15) Cl.** **12-16**

(52) **U.S. Cl.**

USPC **D12/169**; D12/167
